Patented May 27, 1969

214,265

MOTOR-DRIVEN SWAMP BUGGY

Joseph A. Poltorak, 1716 Roberts Road,
Auburn, Mich. 48611

Filed June 11, 1968, Ser. No. 12,306

Term of patent 14 years

Int. Cl. D12—08

U.S. Cl. D14—3

Fig. 3

Fig. 4

FIG. 1 is a side elevational view of a motor-driven swamp buggy showing my new design.

FIG. 2 is a top plan view thereof.

FIG. 3 is a rear elevational view.

FIG. 4 is a front end elevational view.

I claim:

The ornamental design for a motor-driven swamp buggy, substantially as shown.
